(57) **CLAIM**

An ornamental design for a theft deterrent tag having crossing lanyard for use with articles, as shown and described.

DESCRIPTION

FIG. 1 is a perspective view showing a theft deterrent tag having crossing lanyard showing my new design;

FIG. 2 is a top plan view thereof without the lanyards;

FIG. 3 is a bottom plan view thereof without the lanyards;

FIG. 4 is a front end plan view thereof without the lanyards;

FIG. 5 is a back end plan view thereof without the lanyards;

FIG. 6 is a top plan view thereof in an engaged state; and,

FIG. 7 is a bottom plan view thereof in an engaged state.

In the drawings, the broken line showing of a box depicts environmental subject matter and forms no part of the claim.
